(57) **CLAIM**

The ornamental design for a baby stroller with a seat as shown and described.

DESCRIPTION

FIG. 1 is a front view of the baby stroller with a seat showing my new design;

FIG. 2 is a rear-right side perspective view, the rear-left side perspective view being a mirror image thereof;

FIG. 3 is a front-left side perspective view, the front-right side perspective view being a mirror image thereof;

FIG. 4 is a right perspective view, the left side perspective view being a mirror image thereof;

FIG. 5 is the baby stroller with seat of FIG. 1 without the seat folded flat; and,

FIG. 6 is front left side perspective view of FIG. 1 without the seat.
